UNITED STATES PATENT OFFICE.

FELIX MUELLER, OF NEW YORK, N. Y., ASSIGNOR TO STANDARD STOPPER COMPANY, OF NEW YORK, N. Y., A CORPORATION OF NEW JERSEY.

FEEDING MECHANISM.

No. 876,382.

Specification of Letters Patent.

Patented Jan. 14, 1908.

Application filed January 14, 1905. Serial No. 241,134.

To all whom it may concern:

Be it known that I, FELIX MUELLER, a subject of the German Emperor, residing at New York, county of New York, and State 5 of New York, have invented certain new and useful Improvements in Feeding Mechanisms, fully described and represented in the following specification and the accompanying drawings, forming a part of the same.

10 This invention relates to certain improvements in mechanism for feeding receptacles, and has for its object to produce a simple, efficient and positively operating mechanism for feeding receptacles to machines, such, 15 for instance, as bottle capping machines, or other machines in which a positive feed capable of being operated at a high speed is desirable.

With this and other objects not specifically 20 referred to in view, the invention consists in certain constructions, and in certain parts, improvements and combinations, as will be hereinafter fully described and specifically pointed out.

25 Referring to the drawings—Figure 1 is a side elevation, partly in section, of so much of a bottle capping machine as is necessary to an understanding of the invention. Fig. 2 is a section on the line 2—2 of Fig. 1. Fig. 30 3 is a perspective view illustrating a modification.

In the drawings which illustrate embodiments of the invention, 1 indicates a frame or standard in which the operative parts of 35 the mechanism are mounted.

A machine embodying the invention will include some means for presenting the receptacles to a mechanism which is to perform a further operation in connection with 40 the receptacles. This presenting means may be varied in construction and will vary according to the type of machine in which the invention is embodied, and the function of the mechanism which is to operate upon 45 the receptacles. In the particular construction shown, which as before stated represents the invention as embodied in a bottle capping machine, the presenting device will be arranged so that it may be given 50 a movement to successively present receptacles to the mechanism which is to thereafter operate in connection with them.

In the particular construction shown, the

presenting device embodies a star wheel 2 and a table 3. In the preferred construction 55 and as shown, the presenting device will be mounted so as to rotate in order to successively present receptacles, and this rotation will also preferably be effected by mechanism of such a character as to give the presenting 60 device a step by step movement. While the construction by which the presenting device is given this movement may be varied widely, in the construction shown, the presenting device is mounted on a shaft 4 which 65 is preferably held in an inclined position in the frame, as shown, the lower end of the shaft being supported in suitable bearings in a bracket 5, and the upper end of the shaft being held in suitable bearings in a bracket 70 6. The mechanism for giving the shaft 4 the step by step movement referred to may be of any desired character. As shown, the shaft is provided with a disk 7 having slots 8 75 therein on its under side, which slots are successively entered by a pin 9 on a continuously rotating wheel 10. The wheel 10 is mounted on a stud 11 projecting from the main frame of the machine. This movement is of the general character known as a "Geneva" 80 movement, and a specific description of it is unnecessary, as any other desired movement may be substituted therefor. As shown the gear 10 is driven by a gear 12 attached to a bevel gear 13, this gear being driven by intermediates 14 and 15 which derive their motion from the main driving gear 16.

In machines embodying the invention, the receptacles will be positively fed to the presenting device by automatic means. The 90 means for automatically and positively feeding the receptacles may be widely varied in construction. As shown, there is provided a shaft 17 on which is mounted a screw conveyor 18. In the particular construction 95 shown and for reasons to be hereinafter stated, the shaft 17 is a jointed shaft, the joint being indicated at 19. This shaft is supported, in the construction illustrated, in a bearing 20 carried in an arm 21 mounted in 100 a clamp 22 secured to a stud or projection 23 extending from the side of the frame. The shaft 17 is supported at its other end in a bearing 24 formed in an arm 25 which extends from a hub or bearing 26, this hub or 105 bearing being carried on a projection or stud

27 extending outward from the machine frame on the side opposite to that on which the stud 23 is located.

The receptacles may be brought within the 5 range of action of the conveyer in any desired way. In the construction shown, there is provided a table 28 having a guiding rail 29, the table being inclined toward the feeding device so that the receptacles may roll 10 down it by gravity, and being also inclined so that the receptacles will lie upon it in a position substantially parallel to the shaft 4.

In the construction so far described, it 15 will be readily understood that articles placed on the table 28 will roll down the table and the conveyer being suitably driven will positively forward the articles into the range of action of the star wheel which will in turn present them to the mechanism which is to 20 thereafter act in connection with them.

In the preferred construction a machine embodying the invention will include not 25 only means for automatically and positively forwarding the receptacles to the presenting device, but will also provide means for discharging them from the machine after they have been operated upon. While the means for discharging or removing the receptacles 30 from the presenting device may be of any desired character, there is preferably provided a screw conveyer 30, this conveyer being also mounted on the shaft 17, as is clearly shown in Fig. 2. After the articles 35 have been operated upon by the mechanism which is to act in connection with them, a movement of the star wheel brings them within the range of action of the conveyer 30 which automatically and positively moves them away from the presenting device, the 40 receptacles moving over a supporting plate 31 and being delivered onto a receiving table 32. As the receptacles lie in an inclined position in the conveyer 30, a guard 33 is or may be provided which bears against 45 the receptacles near the bottom and brings them up into a vertical position as they pass onto the table 32.

Inasmuch as the conveyer 18 has the receptacles delivered to it by gravity, the receptacles 50 rolling down the inclined plane 28, as has been described, this conveyer 18 will lie in an inclined position, and in order to utilize a single shaft for operating both conveyers, this shaft is made jointed as has been 55 before described. The shaft may, if desired, be additionally supported, arms 34, 35 provided with suitable bearings being shown for this purpose.

The conveyer mechanism may be operated 60 in any desired manner. In the particular construction shown, the shaft 17 is provided with a gear 36 which meshes with a gear 37 carried on a shaft 38, this shaft being supported in a bearing in the arm 25 before referred to and in a similar bearing in an arm

39 similarly located. This shaft 38 is provided with a sprocket wheel 40 over which runs a sprocket chain 41. This chain passes over a second sprocket wheel 42 mounted on a stud extending from the frame which stud 70 also supports a third sprocket wheel 42'. These two sprocket wheels are secured together in any desired manner, the second sprocket wheel being driven from a chain 43 which passes around a sprocket wheel 44 75 screwed on the main driving shaft.

Inasmuch as the invention is shown in connection with a bottle capping machine, a capping mechanism is illustrated in connection therewith. This capping mechanism consists 80 of a capping die 45 mounted on a slide 46 which slide is supported to move in a bracket 47 extending from the main frame and is driven by means of a connecting rod 48 from a crank 49 on the main shaft 50 of the machine, this shaft being the shaft which supports the gear 16 before referred to.

Instead of feeding the bottles into the range of action of the conveyer by gravity, they may, if desired, be manually placed 90 within its range of action, and a construction is illustrated in Fig. 3 by which this can be accomplished. This construction includes a table 51 having a guard rail 52 against which a series of bottles may be placed and along 95 which they may be pushed. The rail 52 terminates at the beginning of the conveyer which in Fig. 3 is marked 53. The conveyer is mounted on a shaft 54 supported in a bearing 55 carried on the table. The driving 100 means for this shaft are omitted as unnecessary to an understanding of this part of the invention, but it will be understood that this shaft may, if desired, be driven in the same manner as the conveyer shaft previously referred to. The table 51 is, as illustrated, horizontally arranged, but the presenting device is inclined, as shown in Figs. 1 and 2. When the construction is arranged in this manner, a guide will be employed for turning 105 the receptacles from a vertical to an inclined position, such a guide being illustrated and marked 56.

It will be understood that when the conveyer mechanism illustrated in Fig. 3 is employed for forwarding receptacles to the presenting device, a conveyer similar to that illustrated in Fig. 2 will be employed for moving the receptacles away from the present device after action has been had upon 120 them by the mechanism which is to operate in connection with them.

The operation of the mechanism will be understood without further specific description than that already given.

It will be seen that the construction is exceedingly simple, and it has been found in practice to be very efficient, as high as one hundred bottles a minute having been successfully fed by it to a capping mechanism. 130

While the mechanism illustrated and described forms an effective means for carrying out the invention, it is to be understood that the invention may be embodied in mechanisms which differ widely therefrom. The invention is not, therefore, to be limited to the specific construction herein illustrated and described.

What is claimed is:—

- 10 1. The combination with a receptacle presenting device, of means for giving it an intermittent movement, a screw conveyer for forwarding the receptacles to the presenting device, and means for automatically presenting the receptacles to the conveyer in an inclined position, the inclination of the receptacles being toward the axis of the conveyer.
- 20 2. The combination with a receptacle presenting device, of means for giving it an intermittent movement, a screw conveyer for positively forwarding the receptacles to the presenting device in an inclined position, the inclination of the receptacles being toward the axis of the conveyer, and a support and 25 guide operating respectively on the bottom and side of the receptacles, said support and guide being inclined with respect to the conveyer so that the receptacles may roll down it into the range of action of the conveyer.
- 30 3. The combination with a receptacle presenting device, of means for giving it an intermittent movement, a receptacle support, a screw conveyer for moving the receptacles along the support to the presenting device, 35 a receiving support, a screw conveyer for for-

warding the receptacles along the receiving support, and means for continuously operating both conveyers.

4. The combination with a receptacle presenting device comprising a star wheel, of a 40 table on which the receptacle rests, means for giving the star wheel an intermittent movement, a support, a screw conveyer for moving the receptacles along the support and into the range of action of the star wheel, a receiving support, and a screw conveyer for moving the receptacles away from the star wheel and along said support, and means for continuously operating both conveyers. 45

5. In a capping machine, the combination 50 with a capping head, of a presenting device, means for giving the presenting device an intermittent movement, means for producing a relative movement between the head and presenting device to bring the receptacle to be 55 capped into the range of action of the capping head, a receptacle support, a screw conveyer for forwarding the receptacles along the support to the presenting device, a receiving support, a screw conveyer for moving the receptacles along this support away from the presenting device, and means for continuously operating the conveyers. 60

In testimony whereof, I have hereunto set my hand, in the presence of two subscribing 65 witnesses.

FELIX MUELLER.
